7-SUBSTITUTED THIO STEROIDS

Robert E. Schaub, Paramus, and Martin J. Weiss, Oradell, N.J., assignors to American Cyanamid Company, New York, N.Y., a corporation of Maine
No Drawing. Filed Aug. 15, 1960, Ser. No. 49,406
12 Claims. (Cl. 260—239.5)

This invention relates to new steroid compounds. More particularly, the invention relates to 7-substituted thio-10 androstanes and androstenes.

The compounds of the present invention can be illustrated by the following structural formula:

in which R_1 is a member of the group consisting of hydrogen and methyl radicals, R_2 is a member of the group consisting of hydrogen and lower alkanoyl radicals, R_3 is a member of the group consisting of hydrogen and lower alkyl radicals, R_4 is a member of the group consisting of lower alkylthio, lower alkylsulfinyl and lower alkylsulfonyl radicals,

is a divalent radical of the group consisting of:

radicals,

is a trivalent radical of the group consisting of:

and

radicals and when R_1 is the methyl radical, R_4 is a lower alkylthio radical,

is the

radical and when

is the

radical, then R_3 is a lower alkyl radical.

The 4-androstene-3-ones of this invention are prepared by treating an appropriate $\Delta^{4,6}$ -3-keto steroid with a lower

alkyl mercaptan or a lower alkyl thiolic acid. These reactions can be specifically illustrated as follows:

and also:

The lower alkylsulfinyl (sulfoxide) derivatives of this invention are prepared by treating the corresponding alkylthio derivative with a slight excess over one molar equivalent of monoperphthalic acid. This reaction is carried out in an inert solvent, such as methylene chloride at room temperature for about 24 hours. The lower alkylsulfonyl (sulfone) derivatives are obtained by a similar treatment of the alkylsulfinyl derivatives with monoperphthalic acid. 35 The latter oxidation usually requires about 48 hours of reaction time. The following equations illustrate these reactions:

wherein Ac is as defined above.

The novel androstane derivatives of the present invention can be prepared from 4-androstene-3-ketones such as 17-acethoxy-7 α -methylthio-4-androstene-3-one which is reacted with lithium in liquid ammonia to saturate the 4,5-double bond and thereby produce an androstane steroid having the trans A/B ring junction. These reactions are 65 illustrated as follows:

wherein Ac is as defined above.

Introduction of the hydroxymethylene group at C-2 is carried out by treating the 4,5-dihydro-3-ketone with an alkyl formate, for example ethyl formate, in the presence of a strong base, such as sodium hydride or sodium alkoxide in benzene at room temperature for a prolonged period such as, for example, five days. Condensation of the hydroxymethylene derivative with hydrazine hydrate to give the pyrazole derivative is easily carried out and can be effected by brief treatment, fifteen minutes usually being sufficient in ethanolic solution at about room temperature. The products of this reaction are obtained by filtration or evaporation of solvents and are purified by crystallization and/or recrystallization techniques well known in the art.

The hydroxymethylene derivatives and the pyrazolo derivatives of this invention may exist in several tautomeric forms. Thus, the product designated as the hydroxymethylene derivative may exist in any one or all of the following structures:

Structural Formula A is the one most commonly designated in the literature for structures of this type and the use of structure A in the specification and claims is intended to include tautomeric forms.

The pyrazolo derivative may have any of the following tautomeric forms (D, E and F).

The use of structure D in the specification and claims is intended to include tautomeric forms.

The process of this invention proceeds under steric influences and stereoisomers are formed. However, one isomer is obtained in predominant amount. The predominant isomer has in each case been characterized herein as possessing the alpha configuration for the 7-lower alkylthio, lower alkanoylthio, lower alkylsulfinyl or lower alkylsulfonyl group. This configuration has been designated in order to provide a more complete exposition of the present invention and in order that the specification shall constitute a more useful contribution to the art. However, the designated configuration of the 7-lower alkylthio, lower alkanoylthio, lower alkylsulfinyl or lower alkylsulfonyl group is based upon an analysis of molecular rotation data presently appearing in the chemical literature and is therefore not to be interpreted except in relation to the state of the art presently known to organic chemists. It will be apparent that no part of the specification will be materially defective if it should later be established that the configuration is the opposite of that deducible from data presently available to workers in the field.

The new compounds of the present invention are particularly useful as androgenic and anabolic agents. They may be used in androgenic-replacement therapy, in supportive therapy for patients suffering from debilitating diseases and in the treatment of post-operative trauma.

The following examples illustrate in greater detail the preparation of the 7-substituted thioandrostanes and thioandrostenes of the present invention.

EXAMPLE I

Preparation of 7 α -Acetylthio-19-Nor-Testosterone Acetate (17 β -Acetoxy-7 α -Acetylthio-19-Nor-4-Androsten-3-One, II)

A solution of 500 mg. of 17 β -acetoxy-19-nor-4,6-androsten-3-one (I) [L. Velluz, B. Goffinet, and G. Amiard, *Tetrahedron*, 4, 241 (1958)] in 2 ml. of freshly distilled thiolicetic acid is heated under reflux for two hours. The reaction mixture is evaporated to dryness under reduced pressure. The residual glass is dissolved in 15 cc. of benzene and chromatographed on 50 g. of silica gel. The column is washed with 300 ml. of 2% ether-in-benzene, 300 ml. of 4% ether-in-benzene, 300 ml. of 6% ether-in-benzene, 350 ml. of 8% ether-in-benzene; these washings are discarded. The column is then eluted with 500 ml. of 10% ether-in-benzene; the eluate is evaporated to dryness under reduced pressure to give 200 mg. of a glass.

The glass is dissolved in 5 ml. of the lower and 5 ml. of the upper phases of the system heptane: methyl Cello-solve and the liquid is mixed with 10 g. of diatomaceous earth. This mixture is packed on top of a column which has been prepared from 100 g. of diatomaceous earth and 50 ml. of the lower phase of the solvent system just described. The column is eluted with the upper phase and the effluent is allowed to pass through a recording spectrophotometer which has been set at 238 m μ . The first 950 ml. of effluent contains little ultraviolet-absorbing material and is discarded. The next 330 ml. contains much ultraviolet-absorbing material. This fraction is taken to dryness to give 136 mg. of product as an amorphous solid; $[\alpha]_D^{25} -59^\circ$ (1.03% in CHCl₃); $\lambda_{\text{max}}^{\text{MeOH}}$ 238 m μ ($\epsilon=18,300$); $\lambda_{\text{max}}^{\text{KBr}}$ 5.71, 5.87, 6.12, 8.00 μ

EXAMPLE II

Preparation of 7 α -Methylthio-19-Nor-Testosterone Acetate (17 β -Acetoxy-7 α -Methylthio-19-Nor-4-Androsten-3-One, III)

A solution of 500 mg. of 17 β -acetoxy-19-nor-4,6-androsten-3-one (I), 1 ml. of concentrated hydrochloric acid and 5 ml. of methyl mercaptan in 35 ml. of glacial acetic acid is allowed to stand at 5-8° C. for four days. The reaction mixture is evaporated to dryness under reduced pressure, and the residue is taken up with methylene chloride and washed with excess saturated sodium bicarbonate solution and then with water. The organic phase, dried with anhydrous magnesium sulfate is evaporated to dryness under reduced pressure to give 400 mg. of a glass. This glass is subjected to partition chromatography on diatomaceous earth by the procedure described above in Example I. The system petroleum ether (B.P. 90-100° C.) methanol-2-methoxyethanol (8:1:1) is used. The column is packed with 300 g. of diatomaceous earth and the recording spectrophotometer is set at 240 m μ . The first 950 ml. of effluent contains only small amounts of ultraviolet-absorbing material and is discarded. The next 400 ml. fraction contains the desired product. This fraction is evaporated to dryness under reduced pressure to give a glass, crystallization of which from acetone-petroleum ether (20-40°) gives 90 mg. of white crystals, melting point 123-125° C. Two recrystallizations from the same solvents raises the melting point to 131-132° C.; $[\alpha]_D^{25} -45^\circ$ (0.65% in CHCl₃); $\lambda_{\text{max}}^{\text{MeOH}}$ 239 m μ ($\epsilon=16,000$); $\lambda_{\text{max}}^{\text{KBr}}$ 5.78, 5.97, 6.15, 7.97 μ

EXAMPLE III

Preparation of 4-Chloro-7 α -Methylthiotestosterone Propionate (4-Chloro-7 α -Methylthio-17 β -Proprionoxy-4-Androsten-3-One, VII)

A solution of 4-chlorotestosterone propionate (IV) [W. J. Adams, D. N. Kirk, and V. Petrow, Brit. Patent 792,727 (1958)] in 120 ml. of reagent carbon tetrachloride is concentrated by distillation to about 100 ml. to remove moisture. To the cooled solution is added 2 ml. of a 10% solution of reagent pyridine in carbon tetrachloride. After flushing with carbon dioxide (bone dry) 1.03 g. of N-bromosuccinimide is added and the solution is heated under reflux for 80 minutes while under illumination with a 60 watt frosted bulb. The cooled solution is filtered, washed with water, dried with anhydrous magnesium sulfate and evaporated to dryness. Crystallization of the residue from hexane by the addition of a few drops of acetone furnishes 2.1 g. (87%) of 6-bromo-4-chlorotestosterone propionate (V), 155-157° dec. Recrystallization from acetone-petroleum ether gives white crystals, melting point 158-160° C. (dec.); $[\alpha]_D^{25} + 185^\circ$ (1.1% in CHCl_3); $\lambda_{\text{max}}^{\text{MeOH}}$ 266 m μ (ϵ 11,200); $\lambda_{\text{max}}^{\text{KBr}}$ 2.95, 3.41, 5.80, 5.93, 7.9 μ

6-bromo-4-chlorotestosterone propionate (V) (1.5 g.) suspended in 15 ml. of sym. collidine and refluxed under an atmosphere of carbon dioxide for 30 minutes, solution being complete at the boiling point. The cooled solution is filtered from collidine hydrobromide and the mother liquid, after being diluted with 100 ml. of benzene, is washed successively with 8% sulfuric acid, saturated aqueous sodium bicarbonate and water, dried with anhydrous magnesium sulfate and evaporated to dryness. The resulting amorphous material (1.1 g.) is dissolved in 25 ml. of benzene and chromatographed on 60 g. of silica gel. The column is washed with 500 ml. of benzene and 1 liter of 1% ether-in-benzene solution; these washings are discarded. The product is eluted by further washing the column with 1% ether-in-benzene solution. The eluates are evaporated to dryness under reduced pressure and the crude residual solid is crystallized from petroleum ether to yield 546 mg. (44%) of 6-dehydro-4-chlorotestosterone propionate (VI), melting point 100-102°. Recrystallization from the same solvent gives 45 white crystals, melting point 103-104°;

$[\alpha]_D^{25} + 79^\circ$ (0.41% in CHCl_3); $\lambda_{\text{max}}^{\text{MeOH}}$ 295 m μ (ϵ 24,600) $\lambda_{\text{max}}^{\text{KBr}}$ 5.73, 5.96, 6.20, 6.42, 8.4 μ

To a cold solution of 6-dehydro-4-chlorotestosterone propionate (VI) (800 mg.) in 50 ml. of glacial acetic acid is added 2 ml. of concentrated hydrochloric acid and then 8 ml. of methyl mercaptan. The solution is kept at 8° C. for eight days.

Evaporation of the reaction mixture gives a syrupy material which is dissolved in methylene chloride. Neutralized with sodium bicarbonate, the solution is washed with water, dried with anhydrous magnesium sulfate and evaporated to dryness. Crystallization of the residual syrup from acetone-petroleum ether gives 85 mg. of product (VII), melting at 235-240° C. Recrystallization from the same solvents gives white crystals, melting point 252-254° C. (dec.);

$\lambda_{\text{max}}^{\text{MeOH}}$ 255 m μ (ϵ 13,800) $\lambda_{\text{max}}^{\text{KBr}}$ 5.72, 5.90, 6.28, 8.40 μ

EXAMPLE IV

Preparation of 7 α -Acetylthio-9 α -Fluoro-11 β -Hydroxy-17 α -Methyltestosterone (7 α -Acetylthio-9 α -Fluoro-11 β , 17 β -Dihydroxy-17 α -Methyl-4-Androsten-3-One, X)

To a solution of 9 α -Fluoro-11 β , 17 β -dihydroxy-17 α -methyl-4-androsten-3-one (VIII) (1.0 g.) [M. E. Herr, et al., J. Am. Chem. Soc. 78, 501 (1956)] in 100 ml. of dry t-butanol, freed from moisture by distillation of 30 ml. of solvent is added 1 g. of chloranil (2,3,5,6-tetra-

chlorobenzoquinone) and 10 mg. of p-toluenesulfonic acid. The mixture is refluxed, under an atmosphere of nitrogen for 20 hours, solution being complete in approximately 45 minutes. The solution is evaporated to dryness under reduced pressure. The residual syrup is dissolved in methylene chloride and the solution is washed with three portions of ice-cold 5% sodium hydroxide solution and then with water (to neutrality), dried with anhydrous magnesium sulfate and evaporated to dryness under reduced pressure leaving an amorphous solid.

Crystallization from acetone-petroleum ether gives 200 mg. of 6-dehydro-9 α -fluoro-11 β -hydroxy-17 α -methyltestosterone (IX) melting point 239° C. dec. Recrystallization from the same solvents gives white crystals, melting point 242° C. dec.;

$[\alpha]_D^{25} + 53.6^\circ$ (0.6% in MeOH); $\lambda_{\text{max}}^{\text{MeOH}}$ 282 m μ (ϵ 28,000); $\lambda_{\text{max}}^{\text{KBr}}$ 2.79, 2.88, 6.03, 6.18, 6.31 μ

A suspension of 6-dehydro-9 α -fluoro-11 β -hydroxy-17 α -methyltestosterone (IX) (100 mg.) in 1 ml. of thiolic acid is refluxed for 18 hours, solution being complete after approximately 25 minutes. The solution is evaporated to dryness under reduced pressure. Trituration of the residual solid with ether gives 88 mg. (72%) of product (X), melting point 241° C. dec. Several recrystallizations from acetone-petroleum ether gives white crystals melting point 243-246° C. dec.;

$[\alpha]_D^{25} + 41^\circ$ (0.24% in CHCl_3); $\lambda_{\text{max}}^{\text{MeOH}}$ 236 m μ (ϵ 19,600); 30 $\lambda_{\text{max}}^{\text{KBr}}$ 2.91, 5.94, 6.04, 6.15, 8.0 μ

EXAMPLE V

Preparation of 7 α -Methylthio-17 α -Methyltestosterone (17 β -Hydroxy-17 α -Methyl-7 α -Methylthio-4-Androsten-3-One, XIV)

A solution of 3 g. of 17 α -methyltestosterone (XI) (commercially available) in 100 ml. of reagent carbon tetrachloride is concentrated by distillation to about 85 ml. to remove moisture. After flushing with carbon dioxide, 1.77 g. of N-bromosuccinimide is added and the solution is refluxed while under illumination with a 60 watt frosted bulb and under an atmosphere of carbon dioxide, for 40 minutes. The solution shows a negative test with moist potassium iodide-starch test paper. The hot solution is filtered and the filtrate is concentrated to dryness under reduced pressure. The residue is taken up in methylene chloride and washed with water, dried with anhydrous magnesium sulfate and evaporated to dryness under reduced pressure leaving a glass. Crystallization from acetone-petroleum ether (boiling point 60-70°) furnishes 2 g. (53%) of 6-bromo-17 α -methyltestosterone (XII), melting point 130-132° C. dec. Three recrystallizations from the same solvent pair gives white crystals, melting point 139-140° C. dec.;

$[\alpha]_D^{25} + 26^\circ$ (0.8% in CHCl_3); $\lambda_{\text{max}}^{\text{MeOH}}$ 246 m μ (ϵ 12,000); $\lambda_{\text{max}}^{\text{KBr}}$ 2.88, 5.93, 6.20 μ

A solution of 1.5 g. of 6-bromo-17 α -methyltestosterone (XII) in 20 ml. of sym-collidine is refluxed, under an atmosphere of carbon dioxide for 45 minutes. The cooled solution is filtered from collidine hydrobromide and the filtrate, after diluting with 100 ml. of benzene, is washed successively with 8% (v/v) sulfuric acid, saturated aqueous sodium bicarbonate and water, dried with anhydrous magnesium sulfate and evaporated to dryness under reduced pressure leaving a semi-solid. Recrystallization from acetone-petroleum ether (boiling point 60-70° C.) furnishes 700 mg. (59%) of 6-dehydro-17 α -methyltestosterone (XIII), melting point 180° C. (gas). Two more recrystallizations from the same solvent pair gives white crystals, melting point 194-195° C.;

$[\alpha]_D^{25} + 33^\circ$ (0.5% in CHCl_3); $\lambda_{\text{max}}^{\text{MeOH}}$ 283 m μ (ϵ 27,200); $\lambda_{\text{max}}^{\text{KBr}}$ 2.91, 6.06, 6.21, 6.34 μ

9

To a cold solution of 932 mg. of 6-dehydro-17 α -methyltestosterone (XIII) in 39 ml. of glacial acetic acid is added 1.5 ml. of concentrated hydrochloric acid and then 7.8 ml. of methyl mercaptan. The solution is kept at 8° C. for six days. The reaction mixture is worked up by the procedure described above in Example III, giving, after crystallization from acetone-petroleum ether, 100 mg. of product (XIV) melting point 192-193° C.;

$\lambda_{\text{max}}^{\text{MeOH}}$ 241 m μ (ϵ 14,600); $\lambda_{\text{max}}^{\text{KBr}}$ 2.83, 6.03, 6.19 μ

EXAMPLE VI

Preparation of 17 β -Acetoxy-7 α -Methylthioandrostan-3-One (XVIII)

A solution of 2.0 g. of 17 β -acetoxy-7 α -methylthio-4-androsten-3-one (XV) [R. E. Schaub and M. J. Weiss U.S. Patent 2,908,694 (1959)] in 25 ml. of dioxane and 25 ml. of ether is added dropwise to a solution of 300 mg. of lithium in 250 ml. of liquid ammonia over a period of 15 minutes. After stirring for an additional 35 minutes the blue color of the solution is discharged by the addition of 6.0 g. of ammonium chloride and the ammonia is allowed to evaporate. The residue is distributed between ether and water and the water extract is washed several times with methylene chloride. The combined organic extracts are washed with water, dried with anhydrous magnesium sulfate and evaporated to dryness under reduced pressure leaving 1.6 g. of amorphous material. Since at least partial deacetylation occurs (17 β -hydroxy-7 α -methylthioandrostan-3-one is present) as indicated by hydroxyl absorption at 2.89 μ in the infrared, the material is acetylated with acetic anhydride in pyridine solution at room temperature overnight. After dilution with water, the mixture is extracted with methylene chloride, washed with water, dried with anhydrous magnesium sulfate and evaporated to dryness under reduced pressure leaving a syrup. Trituration with ether and filtration gives 720 mg. (36%) of 17 β -acetoxy-7 α -methylthioandrostan-3-one (XVIII) as a white powder, melting point 175-179° C. The material has no ultraviolet absorption;

$[\alpha]_D^{25}$ -44.4° (0.61% in CHCl₃); $\lambda_{\text{max}}^{\text{KBr}}$ 5.75, 5.80, 8.00 μ

EXAMPLE VII

Preparation of 17 β -Hydroxy-2-Hydroxymethylene-7 α -Methylthioandrostan-3-One (XIX)

Sodium hydride (2.24 g. of a 5% dispersion in oil) is added to a solution of 2.8 g. of 17 β -acetoxy-7 α -methylthioandrostan-3-one (XVIII) (Example VI) in 100 ml. of reagent benzene and 5.6 ml. of ethyl formate freed from moisture by azeotropic distillation of 20 ml. The reaction mixture is allowed to stand under nitrogen for five days. Methanol (5.6 ml.) is added to decompose the excess hydride and the solution is then diluted with 280 ml. of benzene and 280 ml. of water. The layers are separated and the aqueous phase is extracted with benzene. The aqueous layer is then acidified with dilute hydrochloric acid and the precipitated enol is extracted with ether. The extracts are washed with water, dried with ether. The extracts are washed with water, dried with anhydrous magnesium sulfate and evaporated to dryness under reduced pressure to give a glass. Recrystallization from acetone-petroleum ether gives 1.6 g. (60%) of crystalline product (XIX), melting point 130-140° C. (gas). The compound gives a deep red color with 1% alcoholic ferric chloride solution. Recrystallization from ethyl acetate gives white crystals, melting point 163-165° C. (previous softening);

$[\alpha]_D^{25}$ -29.2° (1.4% in CHCl₃); $\lambda_{\text{max}}^{\text{MeOH}}$ 282 m μ (ϵ 7300); $\lambda_{\text{max}}^{\text{KBr}}$ 2.88, 6.10, 6.25 μ

EXAMPLE VIII

Preparation of 17 β -Hydroxy-7 α -Methylthioandrostan-3-[3,2-c]Pyrazole (XX)

To a solution of 200 mg. of 17 β -hydroxy-2-hydroxy-

10

methylene-7 α -methylthioandrostan-3-one (XIX) (prepared in Example VII) in 7 ml. of absolute alcohol is added 3.0 ml. of absolute alcohol containing 0.03 ml. of 98-100% hydrazine hydrate. The solution becomes turbid and a crystalline material separates after 10 minutes. The mixture remains colorless when tested with 1% alcoholic ferric chloride solution. The mixture is cooled and filtered to give 181 mg. of product (XX) in two crops, melting point 170-173° C. (gas). Several recrystallizations from acetone-water give white crystals, melting point 174° C. (gas);

$[\alpha]_D^{25}$ -22.2° (0.4% in CHCl₃); $\lambda_{\text{max}}^{\text{MeOH}}$ 233 m μ (ϵ 4750); $\lambda_{\text{max}}^{\text{KBr}}$ 3.05, 6.90, 10.46 μ

EXAMPLE IX

Preparation of 7 α -Methylsulfinyltestosterone 17-Acetate (XVI)

To a solution of 7 α -methylthiotestosterone 17-acetate (XVI) (U.S. Patent 2,908,694) (500 mg.) in 10 ml. of methylene chloride is added 1.1 molar equivalents of monoperphthalic acid. The reaction mixture, protected from moisture, is allowed to stand at room temperature for 24 hours, during which period phthalic acid separates. The solution shows a negative test with 20% aqueous potassium iodide solution. The phthalic acid is collected by filtration. The filtrate is washed with dilute aqueous sodium carbonate solution and then with water. After drying over anhydrous magnesium sulfate, the solvent is evaporated at reduced pressure. The residue is triturated with petroleum ether (boiling point 60-70°) and the product (XVI) (77%) is collected by filtration. For analysis, the product is recrystallized from acetone-petroleum ether, melting point 150-152° C.;

$[\alpha]_D$ -6.8° (1% in chloroform); $\lambda_{\text{max}}^{\text{MeOH}}$ 246 m μ (ϵ 11,000); $\lambda_{\text{max}}^{\text{KBr}}$ 5.75, 5.97, 6.15, 8.00, 9.04 μ

EXAMPLE X

Preparation of 17 β -Acetoxy-7 α -Methylsulfinylandrostan-3-One

This product is obtained in 66% yield by the procedure of Example IX from 17 β -acetoxy-7 α -methylthioandrostan-3-one (Example VI). The product is recrystallized from acetone-petroleum ether (boiling point 60-70°); melting point 205-207° C.;

$[\alpha]_D$ -80.6° (1% in chloroform); $\lambda_{\text{max}}^{\text{KBr}}$ 5.78, 5.83, 8.00, 9.60 μ

EXAMPLE XI

Preparation of 7 α -Methylsulfonyltestosterone 17-Acetate (XVII)

This product is obtained in 65% yield from 7 α -methylsulfinyltestosterone 17-acetate (XVI) (Example IX) by the procedure of Example IX. The reaction time is 48 hours. The product is recrystallized from acetone-petroleum ether (boiling point 60-70°); melting point 165-168° C.;

$[\alpha]_D$ +19.7° (1.1% in chloroform); $\lambda_{\text{max}}^{\text{MeOH}}$ 241 m μ (ϵ 15,100); $\lambda_{\text{max}}^{\text{KBr}}$ 5.77, 6.00, 6.16, 7.33, 8.05, 8.88, 13.0 μ

EXAMPLE XII

Preparation of 17 β -Acetoxy-7 α -Methylsulfonylandrostan-3-One

The product is obtained in 92% yield from 17 β -acetoxy-7 α -methylsulfonylandrostan-3-one (Example X) by the procedure of Example XI. Recrystallization from acetone-petroleum ether (boiling point 60-70°) gives material melting at 265-267° C.;

$[\alpha]_D$ -41.5° (0.9% in chloroform); $\lambda_{\text{max}}^{\text{KBr}}$ 5.75, 5.84, 7.73, 8.04, 8.90, 13.04 μ

We claim:

1. The compound 4-chloro-7 α -methylthiotestosterone propionate.
2. The compound 17 β -hydroxy-2-hydroxymethylene-7 α -methylthio-androstan-3-one.
3. The compound 17 β -hydroxy-7 α -methylthioandrostan-[3,2-c]pyrazole.
4. The compound 7 α -acetylthio-9 α -fluoro-11 β -hydroxy-17 α -methyltestosterone.
5. The compound 7 α -methylsulfinyltestosterone-17-acetate.
6. The compound 7 α -methylsulfonyltestosterone-17-acetate.
7. Compounds of the formula:

in which R₅ is lower alkanol and R₆ is lower alkyl-sulfinyl.

8. Compounds of the formula:

in which R₅ is lower alkanol and R₆ is lower alkyl-sulfinyl.

9. Compounds of the formula:

in which R₅ is lower alkanol and R₆ is lower alkyl-sulfinyl.

50

10. Compounds of the formula:

in which R₅ is lower alkanol and R₆ is lower alkyl-sulfonyl.

- 15 11. Compound of the formula:

in which R₆ is lower alkyl.

12. Compound of the formula:

40 in which R₆ is lower alkyl.

UNITED STATES PATENT OFFICE
CERTIFICATE OF CORRECTION

January 22, 1963

Patent No. 3,074,932

Robert E. Schaub et al.

It is hereby certified that error appears in the above numbered patent requiring correction and that the said Letters Patent should read as corrected below.

Column 3, lines 65 to 75, formula XIV, should appear as shown below instead of as in the patent:

column 11, lines 15 to 23, the formula should appear as shown below instead of as in the patent:

column 11, lines 24, 36 and 49, for "alkanol", each occurrence read -- alkanoyl --; lines 28 to 35, the formula should appear as shown below instead of as in the patent:

3,074,932

same column 11, lines 40 to 48, the formula should appear as shown below instead of as in the patent:

column 12, line 13, for "alaknol" read -- alkanoyl --.

Signed and sealed this 17th day of September 1963.
